UNITED STATES PATENT OFFICE.

BANCROFT G. BRAINE, OF NEW YORK, N. Y., ASSIGNOR TO THE RAIL JOINT COMPANY,
OF NEW YORK, N. Y., A CORPORATION OF NEW YORK.

PLURAL-FACED INSULATING UNIT.

1,228,646.

Specification of Letters Patent. Patented June 5, 1917.

Application filed March 21, 1916. Serial No. 86,214.

To all whom it may concern:

Be it known that I, BANCROFT G. BRAINE, a citizen of the United States, residing at New York, in the county of New York and State of New York, have invented certain new and useful Improvements in Plural-Faced Insulating Units, of which the following is a specification.

This invention relates to insulation for rail joints and has for its object a novel construction of insulating unit presenting a plurality of service members or faces whereby a minimum amount of insulating material may be utilized to advantage both electrically and mechanically.

It is well known that the insulating material of an insulated rail joint is subjected to the greatest wear under the head of the rail, so it is, therefore, a special object of the present invention to relieve this condition and effect great economy in the use of insulating material by so constructing the rail-head unit of insulation as to render the entire area of such unit available for service, thereby securing a much greater life for the insulation under the head of the rail, and consequently providing the most economical conditions of maintenance and renewal.

With these and other objects in view, which will more readily appear as the details of the invention are better understood, the invention consists in the novel construction, combination and arrangement of parts hereinafter more fully described, illustrated and claimed.

The invention is susceptible of structural modification, but a practical embodiment thereof is shown in the accompanying drawings, in which—

Figure 1 is a cross-sectional view of an insulated rail joint, including therein rail head insulating units constructed in accordance with the present invention.

Fig. 2 is a side elevation of the joint with the joint bar removed to disclose the novel insulating units.

Figs. 3, 4, and 5 are similar fragmentary sectional views showing the improved rail-head insulating unit in the several different positions which it may occupy to successively bring the different unused portions of the unit into service.

Like references designate corresponding parts in the several figures of the drawings.

In carrying forward the invention the same is applicable to any style of rail joint and to any form of rail-splice or joint bar having a head member engaging beneath the head of the rail. So for the purpose of illustration, there is shown in the drawings one form of insulated rail joint including the rails 1, the joint bars 2, the insulated joint bolts 3, and suitable base insulation 4, for the base flanges of the rails and the lower portions of the joint bars.

The rail-head insulation is the novel and distinctive feature of the present invention, and this rail-head insulation primarily consists of what may be termed a plural-faced insulating unit, having several service members or portions which may be successively brought into service until the entire effective area of the sheet or plate of insulation is completely used up. In its preferable specified embodiment, the said rail-head insulating unit, designated generally by the reference letter U, consists of a plate or sheet of fiber or other equivalent insulating material pressed or bent into the form of a channel plate, thereby adapting the same to telescope over the head member 5 of the bar in all positions of the insulating unit. By reason of this channel formation of the insulating unit the same is provided with a plurality of service members or portions 6, 7 and 8, all preferably of uniform thickness and angularly related.

It will be seen, in the construction described, that the channeled characteristic of the insulating unit U permits the same to fit over the inner head projection of the joint bar as shown in Figs. 3 and 4 of the drawings, or over the top of the joint bar as shown in Fig. 5 of the drawings, according to which service member or portion of the unit is in operative position between the under side of the rail-head and the upper side of the joint bar.

In further explanation of this phase of the invention it will be observed by reference to Fig. 3 of the drawings that when the service member or strip 6 of the insulating unit is in use between the rail-head and the bar-head, the other members or strips 7 and 8 of the unit are disposed at the inner side of the bar to provide for insulation of the joint at this point, but in such position the said members 7 and 8 of the unit are not subjected to the destructive forces of the loads. When

2

the said service member 6 becomes worn or damaged an entirely new insulating surface or area may be brought into use by simply reversing the unit so that the opposite service member or portion 8 may be placed between the rail-head and the bar-head as shown in Fig. 4 of the drawings. And when the said service member 8 of the insulation becomes worn or damaged, the third unused 5 intermediate member 7 of the insulation may be moved into active position between the rail-head and the bar-head as shown in Fig. 5 of the drawings. Thus, the improved insulating unit possesses the capacity of such 10 adjustment that separate portions or members thereof may be separately brought into position between the rail-head and the bar-head, thereby rendering the entire area of the insulation plate or sheet available until 15 the entire unit becomes worn out or destroyed. 20

From the foregoing it is thought that the construction and many advantages of the herein described improvements will be fully 25 understood without further description.

I claim:

1. An insulating unit for the head of a splice bar consisting of an insulation channel plate having a plurality of surface members. 30
  2. A rail-head insulating unit consisting of an insulation channel plate, every member of which is formed to fit between a joint bar and the underside of a rail-head. 35
  3. A rail head insulating unit consisting of an insulation channel plate.
  4. In combination with the rail and the joint bar, of an insulating unit consisting of a channel plate shiftable upon and about the head of the joint bar, and presenting a 40 plurality of surface members.
  5. A rail-head insulating unit consisting of a three-way insulation plate.
- In testimony whereof I have hereunto affixed my signature in the presence of two 45 witnesses.

BANCROFT G. BRAINE.
